SHEET FEEDING MECHANISM

William F. Huck, Richmond Hill, N. Y., assignor
to R. Hoe & Co., Inc., New York, N. Y., a corporation of New York

Application July 25, 1935, Serial No. 33,142

17 Claims. (Cl. 271—20)

This invention relates to feeding mechanism and more particularly to sheet or plate feeding mechanism for use in printing machines.

In printing sheets of metal, card-board or other material of substantial body, the sheets are first stacked upon each other to form a pile, and the sheets are fed preferably one at a time from the top of the pile by a suitable feeding device to the printing mechanism, and, in the present instance, the sheets are printed on a rotary tin or sheet metal printing machine of the offset type. In removing the top sheet from the pile preparatory to conveying it to the printing mechanism by suitable feeding instrumentalities, difficulty is experienced in separating the top sheet from the pile owing to the tendency of the sheet to adhere to the pile either by the effect of static electricity or the adhesive characteristics of the coating or treating material that may be present on the surface of the sheet, therefore, an object of this invention is to provide a sheet feeding mechanism for positively separating each sheet from the pile preparatory to conveying the sheet to the printing mechanism.

Another object of this invention is to provide a sheet feeding mechanism for printing machines incorporating means for buckling the top sheets of a sheet pile preparatory to engaging the top sheet by a suitable suction head or "sucker" and conveying the top sheet by an improved conveying mechanism to the printing mechanism, the conveying mechanism being operated in definite cooperative relation to the feeding and printing mechanism.

A more specific object of this invention is to provide in a sheet feeding mechanism novel means for buckling the top sheets of a feeding pile, the buckling means so engaging the sheets that the top sheets are progressively buckled a greater extent as the sheets are positioned toward the top of the pile, thus entirely separating the top sheet from the remainder of the pile before being engaged by the conveying mechanism.

A further object of this invention is to provide a sheet feeding mechanism for a printing machine in which the top sheet of a feeding pile is engaged by an improved vacuum or suction head, and the suction head and sheet conveyed through a predetermined path of travel to and from the printed mechanism by a novel composite link construction positively operated by a driven component of the printing machine.

Another object of this invention is to provide a sheet feeding mechanism for a printing machine incorporating automatic means for main-

taining the pile of sheets to be fed to the printing mechanism in predetermined relation to the feeding mechanism by improved instrumentalities, and, also, including means for positively raising and lowering the sheet pile through manually controlled power operated instrumentalities independently of the automatic power controlling and operating mechanism.

One of the more specific objects of the invention is to provide a "sucker" in the form of a suction or vacuum head for conveying the sheets from the sheet pile to the printing mechanism, and incorporating simple and positively actuated valve and valve controlling mechanism for positively communicating the suction head to the vacuum pump during the feeding operation, and for communicating the head with the atmosphere to release the feeding sheet.

It is also an object of this invention to provide for use in printing machines a sheet feeding mechanism of generally improved construction, whereby the device will be simple, durable and inexpensive in construction, as well as convenient, practical, serviceable and efficient in its use.

With the foregoing and other objects in view, which will appear as the description proceeds, the invention resides in the combination and arrangement of parts, and in the details of construction hereinafter described and claimed, it being understood that various changes in form, proportion, and minor details of construction may be made within the scope of the claims without departing from the spirit or sacrificing any advantages of the invention.

For a complete disclosure of the invention, a detail description of an improved sheet feeding mechanism for printing machines will now be given in connection with the accompanying drawings forming a part of the specification wherein:

Figure 1 is a fragmental side elevation of an offset sheet or metal printing machine showing the invention applied thereto;

Figure 2 is a detailed diagrammatic view showing the relationship of the components of the improved buckling mechanism and the sheet conveying suction head;

Figure 3 is an enlarged fragmental elevation depicting the suction head and cooperating mechanism, the path of travel of the suction head being shown in dotted lines, and its direction of movement indicated by arrows;

Figure 4 is a fragmental elevation showing the clutch and drive mechanism in the pile hoist

operating device, the view looking in the direction of arrow 4 Figure 11;

Figure 5 is a detailed vertical sectional view taken through the improved sheet buckling roller and supporting frame;

Figure 6 is a fragmental plan view depicting the mechanism for adjusting the thrust block or jaw of the improved sheet buckling device;

Figure 7 is a sectional view taken through the improved crank mechanism for operating the suction head;

Figure 8 is a longitudinal sectional view taken through the valve and valve housing for controlling the communication between the suction head and a suitable vacuum producing source;

Figure 9 is a detailed transverse sectional view of the valve and housing, taken on the line 9—9 of Figure 8;

Figure 10 is a similar view showing the valve in another position;

Figure 11 is a vertical detailed sectional view, parts shown in elevation, taken through the drive end of the improved pile hoist driving mechanism;

Figure 12 is a detailed sectional view taken on the line 12—12 of Figure 11;

Figure 13 is a detailed elevation showing the means for securing the drive gear to the pile hoist screw;

Figure 14 is a detailed vertical sectional view similar to Figure 11 but showing the opposed end of the pile hoist driving mechanism;

Figure 15 is a fragmental elevation depicting the improved safety foot for cooperating with the sheet pile;

Figure 16 is a fragmental plan view of the improved safety foot and supporting mechanism, the view being taken in the direction of arrow 16 of Figure 15; and

Figure 17 is a detailed view showing the ratchet mechanism for operating the pile hoist operating mechanism.

Referring to the drawings, in which similar reference characters designate corresponding parts, there is depicted a rotary offset printing machine having a supporting frame 20 mounted upon the usual bed plate or base 21, and frame 22 for supporting the pile hoist and feeding mechanism. The printing mechanism includes a plate cylinder 23, blanket cylinder 25 and impression cylinder 26 of the usual construction employed in commercial offset machines for printing sheet tin, cardboard or other sheet material of substantial body. The side members of the frame 22 are provided with inwardly extending portions 27 having guide ways or surfaces 28 machined or otherwise formed therein for the sliding reception of supporting lugs 30 extending from platform brackets 31, which are, in turn, suitably secured to the pile hoist platform 32, and the supporting lugs 30 are retained for vertical sliding movement within the guide ways 28 by guide or retaining bars 33. The platform 32 is arranged to support a number of superposed sheets of material to be printed, and in the present instance a plurality of sheets of tin T are illustrated to form the sheet pile, although it is to be understood that any other suitable material of substantial body may be printed and handled in this mechanism. The sheet pile is controlled by and cooperates with instrumentalities of the mechanism to be hereinafter disclosed.

In order to raise and lower the pile platform 32, a pile hoist mechanism is provided which includes a shaft 35 extending transversely across

the machine and mounted for both rotating and sliding movement. The opposed terminals of the shaft 35 are slidably mounted in sleeves 36 rotatably supported by antifriction bearings 37, and the shaft 35 is secured against rotary motion 5 relative to the sleeves 36 by suitable keys 38. Each sleeve 36 is keyed or otherwise suitably secured to a beveled gear 40 which meshes with a beveled pinion 41 rotatably mounted on antifriction bearings 42 supported by a cross brace or 10 rail 43 of the machine frame. A threaded screw 44 is secured to each pinion 41 by suitable pins or keys 45, and a retaining collar 46 is suitably secured to each screw 44 and engages the lower surface of the rail 43 to hold the pinions 41 on 15 the bearings 42 in correct operating position. The supporting lugs 30 of the platform brackets 31 are provided with threaded apertures 47 for the reception of the screws 44, thereby raising and lowering the pile platform when the screws 20 are rotated, as will be hereinafter more fully disclosed.

In order to quickly raise and lower the pile platform to load the platform or to bring the top sheet in proper cooperative relation with other 25 instrumentalities of the feeding mechanism, a reversible push button control motor 48 of the usual commercial type is provided and is suitably secured to the machine frame, as indicated at 49, and this motor is, in turn, connected through the 30 usual commercial worm reduction gear 50 to a stub shaft 51 having a clutch sleeve 52 rigidly secured thereto, and this clutch sleeve is provided with radially extending clutch teeth 53. The end of the shaft 35 which is disposed toward 35 the drive motor 48 is provided with a clutch head 55 which is rigidly secured to the shaft 35, and this clutch head is provided with radially extending teeth 56 for engagement with the teeth 53, as will be hereinafter more fully disclosed. The gears 40 and 41 are positioned in 40 suitable housings 57, and the housing which is positioned toward the drive motor 48 is provided with a bracket 58 in which a lever 60 is pivotally mounted, as indicated at 61. One end of the lever 60 is bifurcated and straddles the clutch 45 head 55, and carries inwardly extending rollers 62 positioned in an annular groove 63 formed in the clutch head 55, to thereby move the shaft 35 longitudinally when the manipulating handle of the lever 60 is moved by an operator. When the 50 operator moves the manipulating handle of the lever 60 and forces the teeth 56 into engagement with the teeth 53, the shaft 35 is then coupled to the drive motor 48, and the operator may raise and lower the pile of sheets T by simply pressing 55 the usual raising and lowering controlling button, not shown, thus controlling the current supplied to the motor 48.

In order to properly feed the sheets T to 60 the printing rollers 25 and 26 of the printing machine, it is necessary to provide a sheet buckling mechanism, a feeding mechanism and means for maintaining the top sheet of the pile at a predetermined height or in predetermined 65 relationship to the feeding mechanism. The preferred form of sheet buckling mechanism includes aligned shafts 65 rotatably mounted in antifriction bearings 66 carried in a cross brace or frame 67 of the machine frame. The bearing portions 68 of each shaft 65 are arranged eccentrically with relation to the shaft body, and the shaft body has spaced antifriction bearings 70 suitably mounted thereon for rotatably supporting a tubular member or shell 71 arranged to 75

engage the longitudinal edges of the top sheets of the sheet pile, as will be apparent from the disclosures hereinafter made. The outer eccentric bearing portion 68 of each shaft 65 has a sprocket 72 rigidly secured thereto, and each sprocket 72 is driven by a chain 73 from a sprocket 74, indicated in dotted lines in Figure 1 of the drawings. A tubular nut 75 is positioned at each side of the machine adjacent the upper terminal of the sheet pile, and each nut 75 is swiveled to the machine frame, as indicated at 76. A threaded screw rod 77 is rotatably received within an axially extending threaded aperture 78 formed in each tubular nut 75, and the outer end of each screw 77 has a worm wheel 80 secured thereto. A worm 81 meshes with each worm wheel 80, and the worms 81 are mounted on a transversely extending shaft 82 rotatably mounted in spaced bearings 83 extending from a thrust or buckling jaw 85, and the terminal of each screw 77 which is positioned toward the thrust jaw 85 is swiveled within the thrust jaw or block, as indicated at 86, and a manipulating handle 87 is secured to one end of the transverse shaft 82, so that by rotating the shaft 82 the worms 81 rotate the worm gears 80, thereby causing the screws 77 to turn in the tubular threaded nuts 75 and move the thrust jaw to and from the tubular buckling member 71, for reasons to be hereinafter pointed out. A shoulder 88 extends longitudinally along the inner vertical face of the thrust jaw 85 and engages and rests on the longitudinal edge of the top sheet T of the sheet pile. To counter-balance the weight of the suspended thrust jaw, an ear 90 extends downwardly from each tubular nut 75, and each ear is pivotally secured to a rod 91 having a helical extension spring 92 mounted thereon and arranged to exert an outward tension against the ear 90 to counter-balance the weight of the thrust or buckling jaw 85.

In order to automatically maintain the top sheet of the sheet pile at a predetermined height or in predetermined relation to the feeding mechanism, to be hereinafter disclosed, the shaft 35 is provided, adjacent its terminal which is removed from the drive motor 48, with a ratchet 93 which is normally loosely mounted on the shaft 35, but may be locked against rotation relative to the shaft 35 by means of a key 95 which extends through a slot 96 in the shaft 35 and engages recesses 97 formed in the ratchet 93 when the shaft is moved in the direction away from the drive motor 48. The ratchet 93 is provided with a plurality of peripheral recesses or teeth 98 to be operably engaged by a pawl 100, which is secured to a rod or shaft 101, as indicated at 102 in Figure 14, and the pawl shaft 101 is carried by spaced arms 103, which are, in turn, rotatably mounted on flanged bearings 105 carried by the frame 22, and bracket 37. A control finger 106 is secured to the pawl shaft 101, as indicated at 107 in Figure 14, and this control finger 106 cooperates with a control arm 108, best shown in Figure 1 of the drawings, for the purpose to be hereinafter pointed out. The spaced pawl actuating arms 103 are oscillated to actuate the pawl by means of an eccentric disc 110 secured to and forming a part of a composite crank mechanism to be hereinafter explained, and this disc 110 is pivotally secured to a link 111, as shown in Figures 1 and 7. The outer terminal of the link 111 is pivotally secured to a bell crank lever 112, which, in turn, is pivotally secured to a link or rod 113, and the outer end

of the rod 113 is pivotally secured to arms 114 secured to the arms 103. Thus, it is seen, as the disc 110 is rotated, the link 111, bell crank 112, rod 113, arms 114 and 103 move the pawl about the shaft 35, thus rotating the ratchet 93 in a clockwise direction, as indicated in Figure 1, when the components are in a position to permit the operable engagement of the pawl 100 with the ratchet 93.

In feeding sheet material to the printing cylinders 25 and 26 of the printing press, it is highly desirable that the sheets T be fed from the sheet pile in a direct path of travel to the feed table and forwarding rollers, and at a speed which during a portion of the feeding travel coincides with the speed of travel of the sheet from the forwarding rollers to the printing cylinders. To accomplish this, applicant provides a suction cup 115 preferably formed of elastic material, such as rubber, and having a disc shaped dished tapered portion 116 for engaging the upper surface of the sheet T, and suitable spaced ribs 117 are provided to maintain the cup in proper shape by adding the necessary rigidity thereto, but, at the same time, permitting the cup to yielding engage the curved surface of the top buckled sheet T and to conform accurately to this surface in order that a suction may be produced. The suction cup or head 115 is secured to a valve housing 118 by suitable screws or fastening devices 120. The valve housing 118 has spaced tubular members 121 secured therein to provide a cylindrical chamber 122 for the reception of the cylindrical valve 123, and the outer terminal portions of the tubular members 121 have relatively short pipe sections 125 rigidly secured thereto and communicating therewith. Spaced arms 126 are pivotally secured around the tubular members 121, as best shown in Figure 8. These arms are pivotally secured at 127 to arms 128, and in order to permit a yielding motion between the short spaced arms 126 and the supporting arms 128, a rod 130 is pivotally secured to each arm 126 and has a helical extension spring 131 positioned therearound and arranged to engage the free terminal of the arm 128 in order that each arm 126 may yield relative to its supporting arm 128 to permit the suction head to yield and conform to the curve surface of the top metal sheet T. The outer terminal of each pipe section 125 is swiveled to an intermediate obliquely-disposed pipe section 132, and the lower terminal of each intermediate pipe section 132 is swiveled to a rigid pipe section 133, which, in turn, leads to a suitable vacuum producing instrumentality, such as a vacuum pump or the like, not shown. The supporting arms 128 are carried by mechanisms provided at each side of the machine, and, of course, a description of the mechanism at one side will describe the duplicate mechanism at the other. Each supporting arm 128 is pivotally secured at its lower terminal, as indicated at 135, to a link 136, and the opposed terminal of the link 136 is movably secured to a composite crank member 137 on antifriction bearings 138, as best shown in Figure 7 of the drawings. Each composite crank 137 is supported for rotary movement by the machine frame 22 and a bracket 24 on interposed antifriction bearings 140 and 141 respectively, these bearings being maintained in operative position in any preferred manner. A shaft 142 extends transversely across the machine and has each terminal secured to and against rotation relative to each composite crank member 137 by means of a key 143, screw 144, 75

and washer 145. Each disc 110 is positioned to align with the shaft 142 so that when the shaft 142 and composite crank members 137 rotate they also rotate the discs 110, thus imparting motion to the ratchet pawl 100 through the hereinbefore described instrumentalities. Each composite crank member 137 is provided with a second antifriction crank bearing 146 on which is rotatably mounted a link 147, and the outer terminal of this link 147 is pivotally secured to a floating bell crank 148, as indicated at 150. The intermediate portion of the floating bell crank 148 is pivotally secured to an intermediate portion of the supporting arm 128, as indicated at 151, and the terminal of the floating bell crank 148 which is remote from the terminal 150 is pivotally secured to an intermediate portion of the link 136, as indicated at 152. Any suitable means may be provided for driving the shaft 142, composite eccentrics 137 and discs 110, and a preferred mechanism for this purpose includes a gear 153 carried by the shaft 142, driven by a gear 155, mounted on a shaft 156, as best shown in Figure 1 of the drawings. The shaft 156 is driven from a stub shaft 157 through intermeshing beveled gears 158 and 160, and the stub shaft, in turn, is driven from a gear train of any preferred type driven from an operating component of the printing machine. Such mechanism is depicted diagrammatically in Figure 1 of the drawings.

The suction head grips the buckled sheets and conveys them from the sheet pile, as will be hereinafter more fully disclosed, and deposits each sheet on a feed table 161 of usual construction into the bite of a driven forwarding roller 162 and a cooperating pressure roller 163, each bearing of the pressure roller 163 being rotatably mounted in a bracket 164, as indicated at 165, and the brackets 164 are mounted for pivotal movement on a transverse shaft 166, each bracket being stressed toward the driven forwarding roller 162 by means of a helical extension spring 167 which is interposed between a cupped extension 168 of the bracket 164 and a rigid lug 170. One of the brackets 164 is provided with an extending finger 171 which engages a terminal 172 of a bell crank 173 which is fulcrumed at 175, and the terminal 172 of the bell crank is normally stressed toward the finger 171 by a helical extension spring 176. The upper terminal 174 of the bell crank 173 is positioned adjacent an operating button or component of the usual commercial limit switch 177 to engage the button and break the electric circuit to the usual driving motor, not shown, when more than one thickness or sheet T of material is fed between the driven forwarding roller 162 and the yieldable pressure roller 163. As the suction head 115 deposits the sheet T upon the feed table 161, and while the suction head is still moving forwardly, the sheet is engaged by the forwarding and pressure rollers 162 and 163. After the suction head 115 moves from engagement with the sheet T, one of the preferably spring pressed pusher fingers 178, carried by a driven chain 180, then engages the rear terminal of the sheet T and cooperates with the forwarding and pressure rollers 162 and 163 in feeding the sheet to grippers 181 carried by the impression cylinder 26, thus causing the sheet T to be fed for printing between the blanket cylinder 25 and impression cylinder 26.

In order that the suction head or cup 115 may be communicated with the vacuum source during

a phase of its operation, and communicated with the atmosphere during another phase of its operation, the valve 123 is provided with a port 182 which communicates with a port 183 formed in the valve housing 118 and the suction cup 115. The valve 123 has a bifurcated arm 185 secured thereto, as indicated at 186, and extending radially therefrom. A roller 187 is mounted for rotation at the outer terminal of the bifurcated arm 185, as indicated at 188, and this roller engages a cam or abutment 190 when the suction head is moved toward the sheet pile, thereby rocking the valve 123 so that the ports 182 and 183 register, thus communicating the suction head or cup with the vacuum source through the port 183, port 182, valve 123, tubular members 121, short pipe sections 125, intermediate pipe section 132, rigid pipe section 133 to the usual vacuum pump, not shown. When the suction head is moved towards the printing cylinders, the roller 187 engages a cam or abutment plate 191, thereby rocking the valve 123 so that a by-pass port 192 formed in its peripheral portion registers with an outlet port 193, formed in the valve housing, and with the port 183, thus causing the vacuum cup 183 to communicate with the atmosphere, thereby breaking the vacuum to release the sheet from the suction head so that it may be deposited on the feed table 161.

To provide a safety device to insure the top sheets T of the sheet pile stopping at the correct or predetermined height when the pile platform is being elevated, the lever 60 has one end of a rod 195 pivotally connected thereto, as shown at 196 in Figure 4, and the opposed end of the rod 195 is pivotally connected to an arm 196, as indicated at 197, in Figure 15. The arm 196 is pivotally secured at its upper terminal to the brace or member 43 of the machine frame, as indicated at 198, and the lower terminal of the arm 196 has a safety member 199 pivotally secured thereto, as indicated at 200. The safety member 199 is in the form of a bell crank having an upwardly extending lever portion 201, normally stressed away from the arm 196 by a spring 202, mounted on a rod 203 operably interposed between the lever 201 and arm 196, and the outward movement of the lever 201 under the stress of the spring 202 is limited by a pin or stud 204 carried by the arm 196, as best shown in Figure 15. A pressure foot 205 extends from the lower portion of the bell crank 199, and this foot is to be engaged by the top sheet T of the pile to operate the safety device, as will be hereinafter disclosed. A commercial limit switch 206 of the conventional type is carried by the machine frame, and this switch is provided with a swinging or rocking arm 207 having a manipulating roller 208 pivotally secured to one terminal, and this roller cooperates with the lever 201, as will be presently explained. When the top sheet T of the sheet pile has been elevated to the desired or predetermined height, this sheet engages the pressure foot 205 and moves it upwardly, thus swinging the lever 201 against the tension of the spring 202 away from the roller 208 of the limit switch 206, thus causing the spring-actuated arm 207 of the switch to move outwardly to the full line position indicated in Figure 15, thus breaking the circuit to the motor 48, thereby arresting the elevating movement of the pile platform. Again, if an operator should attempt to manipulate the lever 60 preparatory to elevating the pile when the top sheet is at or above the predetermined height, the movement of the lever 60 toward 75

clutch-engaging position would cause the pressure foot 205 to engage the top sheet of the pile, thus preventing the lever 201 from moving the limit switch to operating position, thereby preventing the further elevation of the sheet pile.

In operation, if it is desired to quickly elevate or lower the pile platform, this may be done by manipulating the lever 60 to move the teeth 56 of the clutch head 55 into engagement with the clutch teeth 53 of the clutch sleeve 52, and then manipulating the conventional controlling push button for the motor 48, thereby rotating the screw 44 through the described mechanism, thus quickly raising and lowering the sheet pile.

When the top sheet of the pile reaches the desired or predetermined height, it engages the pressure foot 205 of the safety device, thus breaking the electric circuit through the limit switch 206 to the pile platform driving motor 48. After the top sheet has been elevated to the predetermined height, the lever 60 is manipulated to disengage the clutch head 55 from the driving clutch sleeve 52, thus moving the key 95 to engagement with the ratchet 93 to cause the ratchet to be operably connected with the screws 44 through the disclosed mechanism. As the shaft 142 rotates to impart movement to the suction head, it also rotates the disc 110, thereby rocking the pawl 100, through the interposed mechanism hereinbefore disclosed, thus causing the pawl to engage the teeth 98 of the ratchet 93 and impart rotary motion to the ratchet. Whenever the top sheet of the pile is below the predetermined height, the thrust block or jaw 85, which is supported on the upper sheet of the pile by its shoulder 88, causes the control arm 108 to be moved from below the control finger 106, thus permitting the pawl to operably engage the ratchet. However, when the top sheet approaches the predetermined height, the upward movement of the thrust block or jaw 85 swings the control arm 108 under the control finger 106, thus locking the pawl from operable engagement with the ratchet, thereby arresting the upward movement of the pile. The pile supporting platform remains in this position until a sufficient number of the sheets have been fed to the printing mechanism to lower the top sheet below the predetermined height, when the control arm 108 will again release the control finger 106, thus permitting the pawl 100 to engage the ratchet 93 to again elevate the pile.

Rotation of the shaft 142 rotates the composite cranks 137 positioned at each end thereof, and the rotation of these cranks cause the lower terminals of the links 136 and 141 to move in circular paths of travel coinciding with the circular movement of the bearings 133 and 146, and these links 136 and 147 impart movement to the supporting arms 128, through the interposed bell crank levers 148, and the movement of the outer terminal of the supporting arms 128 is influenced by the movement of the swiveled pipe sections 125 and 132, thus causing the suction head 115 to move directly in a short path of travel from the sheet pile to the feed table and to return through a greater arcuate path of travel, as best indicated in Figure 3 of the drawing. Furthermore, during a portion of the movement of the suction head or cup 115 from the pile to the feed table, this suction head moves forwardly at the same speed as the sheets are propelled by the forwarding and pressure rollers 162 and 163, therefore, it is obvious, that as the suction head, at the terminal of its forwarding movement, moves away from the for-

warding path of travel, there is no interruption or break in the continuous feeding movement of the sheet because, as stated, the forwarding and pressure rollers 162 and 163 and the suction head 115 move the sheet forwardly at precisely the same speed. After the suction head conveys the sheet into the bite of the forwarding and pressure rollers 162 and 163, and the sheet moved a distance forwardly by these rollers, a pusher finger 178, in its turn, engages and feeds the sheet to the gripper 181 of the impression cylinder 26, as hereinbefore disclosed, which causes the sheet to be fed in the usual manner between the impression cylinder 26 and the blanket cylinder 25 of the printing machine.

The thrust block or jaw 85 may be adjustably moved along the screws 71 by simply rotating the handle 87, which causes the shaft 82 to rotate the worms 81 which mesh with the worm wheels 80, thereby causing the screws to rotate so that the thrust block or jaw 85 may be adjusted to insure that its shoulder 88 engages the outer longitudinal edge of the top sheet T of the pile.

By interposing the sheets T of the pile to be buckled between the rigid but adjustable jaw 85 and the bodily movable and rotatable cylindrical member 71, great pressure or stress may be exerted against the edge of the sheets without unduly wearing the outer surface of the cylindrical member 71, because, as hereinbefore disclosed, the cylindrical member is free to rotate so that different portions of its peripheral surface is presented to the edges of the engaged sheets during the buckling operations, thereby prolonging the operative life of the buckling mechanism. The cylindrical buckling member 71 is arranged so that its greatest lateral dimension is presented to the top sheet T of the sheet pile thereby causing the peripheral surface of the cylindrical member to engage the sheets of the pile which are positioned below the top sheet at points positioned inwardly relative to the point at which the cylindrical member engages the top sheet to so buckle the sheets that the degree of buckling in each sheet is progressively increased as the sheet is positioned towards the top of the pile to insure the effective separation of the top sheet T from the pile before it is engaged by the disclosed suction head.

What I claim is:

1. In a sheet feeding mechanism for printing machines, means for supporting a pile of sheets, means engaging the vertical edges of the sheets for buckling upwardly a plurality of sheets located at the top of the pile so that the degree of buckling of each sheet is progressively increased as the sheets are located progressively nearer the top of the pile, and a suction head movable to engage the top buckled sheet of the pile and convey it from the pile towards the printing mechanism of the printing machine.

2. In a sheet feeding mechanism for a printing machine, means for supporting a pile of sheets, means for buckling a plurality of the sheets positioned at the top of the pile so that the degree of buckling is progressively increased in each sheet as the sheet is positioned towards the top of the pile, and a suction head movable through different paths of travel and operable to engage the top buckled sheet and convey it from the pile towards the printing mechanism of the printing machine.

3. In a sheet feeding mechanism for a printing machine, means for supporting a pile of vertically aligned superposed sheets, a suction head for engaging and adhering to the top sheet of the pile, and means for moving the suction head upwardly

and then in a relatively short straight path of travel from the pile directly towards the printing mechanism of the printing machine and for returning the suction head to the pile through a different longer path of travel directly above the first path of travel.

4. In a sheet feeding mechanism for a printing machine, means for supporting a pile of vertically aligned superposed sheets, a suction head for engaging and adhering to the top sheet of the pile, and means for moving the suction head in a substantially straight horizontal path of travel of given length from the pile in a direction directly towards the printing mechanism of the printing machine and for returning the suction head to the pile through another arcuate path of travel of greater length directly above the first path of travel.

5. In a sheet feeding mechanism for a printing machine, means for supporting a pile of sheets, a suction head for engaging and adhering to the top sheet of the pile, a conveyor mechanism movable from a point between the pile and the printing mechanism of the printing machine 25 in a direction towards the printing machine at a given speed to convey the sheet from the said point to the printing mechanism, and means for moving the suction head from the point at which it adheres to the sheet first upwardly from the pile and then in a direct substantially horizontal path of travel of given length in a direction towards the conveyor mechanism to convey the sheet to the conveyor mechanism and from there through an arcuate path of travel of greater 35 length in a direction away from the conveyor mechanism along a path of travel located directly above the said horizontal path back to the pile of sheets.

6. In a sheet feeding mechanism for printing machines, means for supporting a pile of vertically aligned superposed sheets, a suction head for engaging and adhering to the top sheet of the pile, a conveyor mechanism movable towards the printing mechanism of the printing machine at 40 a given speed to convey sheets to the printing mechanism, and means for moving the suction head first upwardly from the point at which it engages and adheres to the sheet and in a direct substantially horizontal path of travel from the pile to the conveyor mechanism to convey the sheet from the pile to the conveyor mechanism, the suction head moving in a portion of the path of travel at a speed equal to the speed of the conveyor mechanism and movable in other portions of the path of travel at a different speed.

7. In a sheet feeding mechanism for printing machines, means for supporting a pile of sheets, a suction head for engaging and adhering to the top sheet of the pile, a conveyor mechanism movable substantially horizontal in a direction from the pile towards the printing mechanism of the printing machine at a given speed to convey sheets to the printing mechanism, and means for moving the suction head in a substantially horizontal direct path of travel from the pile to the conveyor mechanism at a speed equal to the speed of horizontal travel of the conveyor mechanism to convey sheets from the pile to the conveyor mechanism and for returning the suction head 70 from the conveyor to the pile through another longer path of travel at a different speed.

8. In a sheet feeding mechanism, means for supporting a pile of sheets, a jaw engaging an edge of each of a plurality of sheets positioned at the top of the pile, a rotatable member en-

gaging the opposed edge of each of the same sheets and movable bodily toward the jaw for buckling the sheets between the movable member and the jaw.

9. In a sheet feeding mechanism, means for supporting a pile of sheets, a jaw engaging an edge of each of a plurality of sheets positioned at the top of the pile, a rotatable cylindrical member engaging the opposed edge of each of the same sheets and movable bodily toward the jaw 10 to buckle the sheets between the cylindrical member and the jaw.

10. In a sheet feeding mechanism, means for supporting a pile of sheets, a jaw engaging an edge of each of a plurality of sheets which are 15 positioned at the top of the pile, a cylindrical member mounted for turning movement on bearings and engaging the opposed edge of each of the sheets which are engaged by the jaw, the cylindrical member being movable bodily towards 20 the jaw to buckle the engaged sheets between the cylindrical member and the jaw.

11. In a sheet feeding mechanism, means for supporting a pile of sheets, a jaw engaging one edge of each of a plurality of the sheets which 25 are positioned at the top of the pile, a cylindrical member mounted for turning movement on bearings and engaging the opposed edge of each of the sheets which are engaged by the jaw, means for driving the cylindrical member to move it 30 bodily towards the jaw to thereby buckle the engaged sheets between the cylindrical member and the jaw.

12. In a sheet feeding mechanism, means for supporting a pile of sheets, a jaw engaging one 35 edge of each of a plurality of the sheets which are positioned at the top of the pile, means for rotatably supporting a shaft having an eccentric portion, a cylindrical member mounted for turning movement on the eccentric portion of the 40 shaft and engaging the opposed edge of each of the sheets which are engaged by the jaw, and means for rotating the shaft thereby causing its eccentric portion to bodily move the cylindrical member towards the jaw to thereby buckle the 45 engaged sheets between the cylindrical member and the jaw.

13. In a sheet feeding mechanism, means for supporting a pile of sheets, a jaw engaging one edge of each of a plurality of the sheets which 50 are positioned at the top of the pile, a rotatable cylindrical member engaging the opposed edge of each of the same sheets and positioned so that its greatest diameter engages the top sheet, and means for bodily moving the cylindrical member 55 towards the jaw for buckling the sheets so that the degree of buckling is progressively increased in each sheet as the sheet is positioned toward the top of the pile.

14. In a sheet feeding mechanism for printing 60 machines, means for supporting a pile of sheets, a suction head for engaging and adhering to the top sheet of the pile, swiveled pipe sections communicating the suction head with a vacuum producing source, and a driven composite mechanism coaxing with the swiveled pipe sections to support and move the suction head through one path of travel from the pile towards the printing mechanism and through a greater path of travel back to the pile.

15. In a sheet feeding mechanism, means for supporting a pile of sheets, a jaw engaging the edges of some of the sheets, a cylindrical member engaging the opposed edges of the sheets which are engaged by the jaw, the cylindrical 75

member being mounted for free rotation to present different portions of its peripheral surface to engage the sheets and movable bodily towards the jaw to buckle the engaged sheets between the 5 cylindrical member and the jaw.

16. In a sheet feeding mechanism for printing machines, means for supporting a pile of sheets, a suction head for engaging and adhering to the top sheet of the pile, swiveled pipe sections communicating the suction head with a vacuum-producing source, a driven crank mechanism, a supporting arm yieldably secured to the suction head, movable members operably interposed between the crank member and the supporting 10 arm, the swiveled pipe sections, crank member, supporting arm and interposed movable member 15 cooperating to move the suction head in a short path of travel from the pile towards the printing mechanism and through a greater path of travel 20 back to the pile.

17. In a sheet feeding mechanism for a printing machine, means for supporting a pile of sheets, a suction head, means for moving the suction head in a direct path of travel from the pile towards the printing mechanism of the printing machine and for returning the head through a greater path of travel to the pile, abutments positioned in the paths of travel of the suction head, swiveled pipe sections leading from a vacuum-producing source to the suction head, a valve 5 carried by the suction head and operably interposed between the suction head and swiveled pipes, the valve engaging the abutments when the suction head is moved in its paths of travel 10 to move the valve to either vacuum connection or break positions to thereby cause the suction head to adhere to or release the top sheet of the pile. 15

WILLIAM F. HUCK. 20
